DISPENSING CONTAINER

Frank J. O'Brien, Pelham, N. Y., assignor to Continental Can Company, Inc., New York, N. Y., a corporation of New York

Application April 8, 1939, Serial No. 266,807

2 Claims. (Cl. 221—26)

The present invention relates to new and useful improvements in dispensing containers, and more particularly to improvements in a container having a bung closure and a pouring spout adapted to be attached thereto for dispensing the contents of the container.

An object of the present invention is to provide a dispensing container of the above type wherein the pouring spout is provided with a 10 depending open-ended wall portion extending within and adapted to be detachably connected to the bung closure, the bottom wall of which may be punctured throughout substantially the entire extent thereof for providing a dispensing 15 opening adapted to register with the open end of the depending wall portion of the spout.

A further object of the invention is to provide a dispensing container of the above type wherein a friction closure plug is adapted to fit 20 within the depending wall portion of the pouring spout in order to re-seal the container after the bottom wall of the bung closure has been punctured and a portion of the contents has been dispensed.

25 A still further object of the invention is to provide a dispensing container of the above type wherein the bung closure is provided with a depending side wall extending within the container, this side wall being provided with inwardly directed holding means adapted to cooperate with similar holding means on the depending wall portion of the pouring spout whereby to detachably connect the spout to the closure.

30 The above and other objects of the invention will in part be obvious and will be hereinafter more fully pointed out.

In the accompanying drawing,

Figure 1 is a top plan view of a container 40 with the pouring spout attached to the bung closure and with the friction closure plug attached to the pouring spout, the pouring spout being shown in dotted lines disposed within the side wall of the container.

45 Figure 2 is an enlarged fragmentary side view, in section, taken along the line 2—2 of Figure 1.

Figure 3 is a detail sectional view of the pouring spout.

50 Figure 4 is a detail sectional view of the friction closure.

Referring more in detail to the accompanying drawing, one form of the invention is shown for purposes of illustration. In this form of the invention, there is shown a container having a substantially rectangular body portion 10 to

5 which a can end 11 is secured by the usual double seam 12. It is to be clearly understood, of course, that the body portion of the container may be of any desired shape and that the can end 11 may be secured thereto in any suitable manner. The can end 11 is provided with an upstanding neck portion 13 which extends around the edge of a filling opening therein. The neck portion 13 is illustrated as being slightly inclined outwardly toward the free edge 10 thereof.

A cup-like bung closure is provided for closing the filling opening in the can end 11, and this bung closure includes a depending wall portion 14 and a bottom wall portion 15 which is 15 disposed within the body portion of the container. The depending wall portion 14 is similarly inclined with respect to the neck portion 13 on the can end 11, that is, the wall portion 14 20 is slightly inclined inwardly. The free edge 14a of the wall portion 14 is shaped to overlie and engage the neck portion 13 on the can end 11. The edge 14a and the neck portion 13 may be secured together in any suitable manner. The 25 depending wall portion 14 of the bung closure is provided with an inwardly extending bead 16 which is illustrated as being disposed intermediate the ends of the wall portion 14 and below the can end 11 and which is also spaced above the bottom wall 15 of the bung closure. This 30 inward bead 16 provides an annular holding flange for removably and rotatably securing a pouring spout thereto in a manner to be more fully pointed out. The bottom wall 15 of the bung closure includes a central portion 15a which 35 is defined by a circular score line 17. The portion 15a within the score line 17 provides a portion of substantially the entire extent of the bottom wall 15 which may be removed to provide a dispensing opening through which the 40 contents of the container may be poured.

A pouring spout 18 is constructed so that it may be removably and rotatably attached to the bung closure. The pouring spout is provided with a pouring lip portion 19 and a depending 45 substantially cylindrical wall portion 20 in rear of the pouring lip. The edge of the pouring spout is provided with an outward bead 21 which serves to strengthen the same and the depending wall portion 20 is open so as to provide an opening 22 which substantially registers with the removable portion 15a in the bottom of the bung closure. Thus, when the portion 15a is removed from the bottom of the bung closure, the 50 contents of the container may be directed through 55

the opening 22 to the pouring lip 19. The bottom edge of the depending wall portion 20 on the spout 18 is shaped to provide an outward beard 23 which is slightly resilient due to the provision of the opening 22. This outward beard 23 is adapted to fit beneath the inward bead 16 on the depending wall 14 of the bung closure so that the pouring spout may be removably attached thereto. Thus, the diameter of the wall portion 20 of the pouring spout is less than the diameter of the edge 14a of the bung closure which is secured to the neck portion 13 in the can end.

A cup-shaped friction closure plug 24 is provided with a vertical and substantially cylindrical wall portion 25 and a closed bottom wall 26. The free edge of the vertical wall 25 is provided with an outward strengthening bead 27. The vertical wall portion 25 of the friction closure 24 is adapted to extend within and to frictionally engage the inner surface of the depending wall portion 20 on the pouring spout 18 above the bead 23. When the friction closure 24 is in this position, the bottom wall 26 thereon serves to close the opening 22 at the bottom of the pouring spout 18. The side walls of the pouring lip 19 are extended outwardly and are suitably shaped so that the outward bead 27 on the friction closure 24 is disposed adjacent the rear portion of the bead 21 on the pouring spout and adjacent the rear portion of the pouring lip 19.

When the container has been filled and the bung closure secured to the upstanding neck portion 13 around the filling opening therein, the pouring spout 18 may be attached directly to the bung closure, or it may be furnished separately for subsequent attachment thereto. Likewise, the friction closure 24 may be within the depending wall portion 20 on the pouring spout and thus transported as a unit. In attaching the pouring spout 18 to the bung closure, it is forced inwardly of the bung closure so that the inward bead 16 on the bung closure and the outward bead 23 on the pouring spout will give slightly so as to afford a snap fitting between the spout and the bung closure. Thus, the pouring spout may be rotated relative to the can end so that the lip portion 19 thereof may extend beyond the double seam 12 in a dispensing position and be disposed within the side wall of the container in an operative position.

When it is desired to dispense the contents of the container, or a portion thereof, the friction closure 24 is removed and the portion 15a of the bottom wall 15 of the bung closure is removed along the score line 17 so as to provide a dispensing opening. When the pouring lip 19 extends over the edge of the container, the contents thereof may be directed through the dispensing opening, the opening 22 in the depending wall 20 of the spout and to the pouring lip 19. If only a portion of the contents of the container is to be dispensed, the friction closure 24 may be fitted within the depending wall portion 20 on the pouring spout so as to close the opening 22 therein. Thus, the friction closure 24 provides a re-seal or re-closure for preventing further dispensing of the contents of the container.

While one form of the invention has been shown for purposes of illustration, it is to be clearly understood that minor changes in the details of construction and arrangement of parts may be made without departing from the scope of the invention as set forth in the appended claims.

I claim:

1. A container comprising a body portion, a container end secured to said body portion and 10 having a filling opening therein, a closure for the filling opening having a bottom wall provided with a scored portion adapted to provide a dispensing opening and a depending side wall fitting within the filling opening, said depending side 15 wall being secured to the container end around the filling opening therein and having an inwardly extending bead intermediate the ends thereof and spaced above the said bottom wall, a 20 spout having a pouring lip and a depending open-ended wall portion adapted to extend within the side wall of said closure, the depending side wall of said spout having at the bottom thereof an outwardly extending bead adapted to snap beneath the inwardly extending bead on the side 25 wall of said closure for removably attaching the closure and the spout, and a closure plug adapted to frictionally engage the entire inner surface of the depending side wall of said spout above said outwardly extending bead for re-sealing the 30 container after the dispensing opening has been formed and a portion of the contents removed.

2. A container comprising a body portion, a container end secured to said body portion and having a filling opening therein, a closure for the 35 filling opening having a depending side wall extending within the filling opening and a bottom wall disposed within the container, the side wall of said closure being secured to the container end around the filling opening therein and having an inwardly extending bead intermediate the 40 ends thereof and disposed within the container and spaced above the said bottom wall, the bottom wall of said closure having a central portion defined by a score line and of substantially the 45 entire extent thereof for providing a dispensing opening, a spout having a pouring lip and a depending open-ended wall portion adapted to extend within the side wall of said closure, the opening in the depending wall portion of said 50 spout being substantially in register with the scored central portion in the bottom wall of said closure and the said depending side wall of said spout being provided at the bottom thereof with an outwardly extending bead adapted to snap 55 beneath the inwardly extending bead on said closure for removably attaching the spout and the closure, and a closure plug having a depending side wall adapted to frictionally fit within and engage the entire inner surface of the depending 60 wall portion of said spout above said outwardly extending bead and having a closed bottom wall adapted to close the opening in the depending wall portion of said spout and also the dispensing opening in said closure whereby the container may be re-sealed after a portion of the contents thereof have been dispensed.

FRANK J. O'BRIEN.
